UNITED STATES PATENT OFFICE.

EDWARD M. HEWLETT, OF SCHENECTADY, NEW YORK, ASSIGNOR TO GENERAL ELECTRIC COMPANY, A CORPORATION OF NEW YORK.

HIGH-POTENTIAL INSULATOR.

1,077,711.

Specification of Letters Patent.

Patented Nov. 4, 1913.

Application filed May 5, 1908. Serial No. 430,987.

To all whom it may concern:

Be it known that I, EDWARD M. HEWLETT, a citizen of the United States, residing at Schenectady, county of Schenectady, State 5 of New York, have invented certain new and useful Improvements in High-Potential Insulators, of which the following is a specification.

The present invention relates to insulators 10 for electric conductors, and more particularly to insulators of the post type for conductors carrying currents of exceedingly high potential.

The ordinary form of insulator post is de- 15 signed to be mounted on a wood or iron pin which extends through a central bore to near the top of the insulator to which the electric conductor is attached. The iron pins are good conductors at all times and the wood 20 pins are good conductors when wet and fair conductors when dry, especially when the circuit conductor is under high potential, so that the electric stresses acting to break down or puncture the insulating wall be- 25 tween the pin and the circuit conductor are localized at the weakest section of the insulator, in the vicinity of the end of the supporting pin.

The object of my invention is to provide 30 an insulator of the post type which may be mounted without a supporting pin and in which the electric stresses will be widely distributed and the tendency to rupture reduced to a minimum.

In carrying out the invention, I provide a 35 long insulator post consisting of a plurality of transverse sections securely connected end to end, and connect the post to its support by a clamp which engages the larger 40 end thereof, while the circuit conductor is secured by means engaging the opposite end of the post, thereby leaving practically the full length of the post in a condition to operate as a barrier to the passage of current from the electrified parts carried thereby to the support on which the post is mounted.

For a more complete understanding of the 50 invention, reference may be made to the accompanying drawings forming a part of this specification, in which—

Figure 1 shows two posts, one in side elevation and one in longitudinal section with a circuit breaker or switch mounted on

the outer ends thereof; Fig. 2 is an end elevation; and Fig. 3 is an enlarged side elevation of the outer ends of the posts and the parts carried thereby.

The insulator post, as shown in Fig. 1, consists of three sections 1, 2 and 3 of ceramic or other suitable insulating material made frusto-conical in shape and hollow. It is to be understood that the number of sections may vary according to the potential of the circuit carried by the posts. The larger 60 base section 1 is formed with a peripheral flange 4 at its larger end with which a clamp 5 is adapted to engage. The clamp consists of segmental plates having flanges through which the wall bolts 6 are adapted to pass. 70 The smaller end of section 1 has a rabbeted recess 7 for receiving a complementary projection 8 of section 2 and a securing medium 9 of glaze, cement, etc. The upper end of section 2 is formed substantially like the 75 smaller end of section 1 for the reception of a complementary projection on outer section 3. Section 3 is closed at its smaller end and provided with a peripheral groove 10 for the reception of the clamping means by 80 which the electrified parts are secured to the post. The exterior surface of the post is ribbed or fluted in order to increase the creepage surface. The inner surfaces of the several sections have a series of grooves 11 85 formed therein in order to provide a greater creepage surface for the electric current in case the material of which the insulator is formed should become cracked or ruptured.

The metallic caps 12 carried by the 90 smaller ends of the post are formed with two main side arms 13 which extend on opposite sides of the insulator into line with the groove 10 and transversely apertured for the reception of screw-threaded ends of 95 a U-shaped clamping band 14. A segmental connection 15 extends from one arm 13 to the opposite arm and is adapted to lie in the groove 10, and a third arm 16 connects the middle point of the connector with the 100 main portion of the cap. A packing member 17 of flexible fiber is interposed between the clamping members 14 and 15 and the bottom of the groove 10. Each of the arms 13 and 16 has a diagonally tapped hole for 105 the reception of a set screw 18 which impinges at its inner end against a ring or plate 19 resting against the end of the post

whereby the cap 12 may be accurately positioned or leveled with relation to the post and also a certain tension imposed upon the clamping means. The caps 12 carry on their outer surfaces contact clips 20 which are secured thereto by screws 21, and in the construction shown the upper contact clip 20 is adapted to receive the free end of a switch blade 22 and has a latch 23 pivoted thereon and tensioned by a spring 24. The lower contact clip 20 is made double to receive the bifurcated end of the switch blade 22. The switch blade is preferably provided with an S-shaped hook 25 whereby the switch may be opened or closed by a pole hook (not shown) and also with a stop projection 26 near the hinged end which is adapted to engage the lower contact clip 20 when the blade is in open position as indicated in dotted lines in Fig. 3. Terminals 27 for the circuit conductors are connected to the respective contact clips by means of nuts 28.

I do not desire to restrict myself to the particular form or arrangement of parts herein shown and described, since it is apparent that they may be changed or modified without departing from my invention.

What I claim as new and desire to secure by Letters Patent of the United States, is,—

1. The combination with an insulator post, of a metallic cap having means for coupling to the end of said post, and means for angularly adjusting or leveling said cap thereon.

2. The combination with an insulator post having a grooved end, of a metallic cap having a clamp for engaging the said grooved end, an adjustable means carried by said cap for angularly adjusting or leveling it with relation to the said post.

3. The combination with an insulator post, of a metallic cap having means for coupling to the end of said post, a plate on the end of said post, and means carried by the cap for engaging said plate and operating to adjust or level said cap with relation to said post.

In witness whereof, I have hereunto set my hand this 2nd day of May, 1908.

EDWARD M. HEWLETT.
